UNITED STATES PATENT OFFICE

156,614

TONE CABINET

Wilfred C. Ernst, Chicago, Ill., assignor to Central Commercial Company, Cook County, Ill., a corporation of Illinois

Application December 23, 1948, Serial No. 150,342

Term of patent 14 years

(Cl. D56—4)

To all whom it may concern:

Be it known that I, Wilfred C. Ernst, a citizen of the United States, residing at Chicago, in the county of Cook and State of Illinois, have invented a new, original, and ornamental Design for Tone Cabinet, of which the following is a specification, reference being had to the accompanying drawing, forming a part thereof.

The figure is a perspective view of a tone cabinet showing my new design.

I claim:

The ornamental design for a tone cabinet, as shown.

WILFRED C. ERNST.
